UNITED STATES PATENT OFFICE.

EDWARD BUSS, OF ST. GALLEN, AND RUDOLF KÜHN, OF RORSCHACH,
SWITZERLAND.

LOCOMOTIVE.

SPECIFICATION forming part of Letters Patent No. 296,129, dated April 1, 1884.

Application filed October 8, 1883. (No model.) Patented in France January 8, 1883.

To all whom it may concern:

Be it known that we, EDWARD BUSS, engineer, a citizen of the Republic of Switzerland, residing in St. Gallen, Switzerland, and RU-
DOLF KÜHN, engineer, a citizen of the Republic of Switzerland, residing in Rorschach, Switzerland, have invented Improvements in Locomotives, of which the following is a specification.

Our invention, relating to steam-engines, is shown embodied in a locomotive, and has for its object to eradicate the disturbing forces and vibration resulting from the momentum of the reciprocating parts, thus making the pressure on the driving-wheels substantially equal in all positions of the crank. The disturbing forces arising from the momentum of the actuating parts of the engine produce two different kinds of movement in the body of the locomotive, one an oscillating movement about a vertical axis through the center of gravity, the number of oscillations being the same as the number of revolutions of the driving-wheels, and the second disturbing movement being a reciprocating movement of the entire body of the locomotive caused by the momentum of the reciprocating parts of the engine. There are other disturbing forces, which are, however, of less amount, and need not be taken into consideration in connection with the present invention. The effect produced by the revolving parts of the engine can be neutralized by counter-weights on the driving-wheels of proper amount and in proper position to balance the revolving parts—viz., the crank-pins, parallel rod, and a portion of the connecting-rod adjacent to the crank-pin. If, however, the revolving counter-weight is made of sufficient weight to counterbalance also the weight of the reciprocating parts, the forces acting on the wheel will vary in the different positions of the crank, thus producing an unbalanced centrifugal force on the wheels and increasing the tendency of the locomotive to jump off from the track, and also increasing the wear and tear arising from unbalanced pressure, and tending to produce uneven wear on the tires of the wheels.

The present invention consists in the combination of the actuating parts of a reciprocating engine with a reciprocating counter-weight and connecting mechanism between it and the reciprocating parts of the engine, whereby the said counter-weight is caused to move in an opposite direction to the said reciprocating parts, and with substantially the same relative velocity in the different parts of its movement; and the invention also consists in details of construction of the connecting mechanism by which the counter-weights are actuated.

Figure 1 is a side elevation of a portion of a locomotive embodying this invention, the driving-wheel being shown at about the half-stroke, while the reciprocating parts are shown at about the end of the stroke; Fig. 2, an end elevation of the reciprocating parts and their counter-weight; Fig. 3, a plan view of the said parts shown in Fig. 2; Figs. 4 and 5, side and end elevation of a modification, and Figs. 6 and 7 similar views of another modification.

The locomotive, a portion only of which is shown, may be of any suitable or usual construction, the driving-wheel *a* being provided with a counter-weight, *b*, of sufficient amount to balance the crank-pin and that portion of the parallel rod *c* and connecting-rod *d* that is carried thereby, and that has nearly the same rotary movement as the said wheel. The piston-rod *e* may be connected with the connecting-rod *d* in the usual manner, and is shown in this instance as connected with and guided by levers *f*, pivoted upon pins *f'*, connected with the ends of supporting-levers *g*, themselves pivoted at *g'* to a yoke or frame, *h h'*, secured by a bracket, *i*, upon the frame *k* of the locomotive. The axis *g'* of the lever *g* intersects the axis of the cylinder and piston-rod of the engine. The ends *f''* of the levers *f* are pivoted in blocks that are free to slide in vertical guides *h''* in the frame *h h'*, and the arms of the levers *f* and of the levers *g* being all equal, they constitute a parallel-motion device by which the piston-rod *e* is guided in a straight line and the vertical thrust of the connecting-rod *d* sustained. The other ends of the levers

g are connected with levers *m*, having one end pivoted in blocks *n*, sliding in vertical guides *h*³ in the frame *h h'*. The other ends of the said lever *m* sustain the counterbalancing-weights *o*, which thus receive a parallel motion in the plane of the axis of the engine-cylinder and piston-rod, and in opposite direction to the said piston-rod, the velocity of the counter-weight being the same as that of the piston-rod in all parts of its movement.

It will be seen that the counter-weights and mechanism by which they are connected with the piston-rod and actuated are symmetrically arranged with relation to the axis of the engine-cylinder, so that the center of gravity of the said parts all travel in the said axis, and by making the counter-weights *o* equal in weight to the reciprocating parts—viz., the piston, piston-rod, and portion of the connected rod *d* adjacent thereto—the momentum of the said reciprocating parts will be perfectly balanced and will have no tendency to vibrate the body of the engine backward and forward, as is the case when no such counter-weights are used.

By the employment of the counter-weights *b* to balance the rotating parts of the locomotive and the counter-weights *o* to balance the reciprocating parts, it will be seen that scarcely any strain is received by the engine from the momentum of its moving parts.

It is obvious that the construction and arrangement of the parts by which the counter-weights are connected with and actuated by the reciprocating parts of the engine may be greatly varied without departing from our invention, and the said connecting mechanism need not necessarily also constitute the guide for the piston-rod; but the usual guides and cross-head may be employed and counter-weights connected therewith by any mechanism which will cause them to move in the opposite direction to and with a velocity proportional to that of the reciprocating part of the engine throughout its movement.

The modifications shown in Figs. 4 to 7, inclusive, represent the reciprocating counterbalance as applied to engines already in use with comparatively slight alteration in the said engines. In Figs. 4 and 5 the usual cross-head, *p*, has connected with it, at its opposite upper and under side, arms *p' p'*, connected by links *r' r'* with levers *t' t'*, pivoted at either side of the cross-head guides, and supporting the counter-weights *o' o'*. It will be seen that in this construction the two counter-weights do not move

in a straight path, but in an arc around the pivotal points of the levers *t' t'*; but they will be always at equal distances from the axis of the piston-rod and cylinder, so that the center of gravity of the pair of weights will move in a direct line along the said axis in the opposite direction to the movement of the cross-head, as is desired. In the construction shown in Figs. 6 and 7 the cross-head *p'* is connected by links *r* with levers *t¹⁰*, pivoted upon bearing-pedestals *u¹⁰* upon the cross-head, and connected with the weight-carrying levers *t¹²*, the fulcrum of which is movable on a short arm or link, *t¹³*, pivoted on a bracket, *u¹²* at the side of the boiler. The length of the lever-arms is such as to give the weights *o¹⁰* a substantially-rectilinear movement in the plane of the axis of the engine-cylinder.

We claim—

1. The combination of the reciprocating parts of an engine with the counterbalancing-weight and connecting mechanism between the said weight and reciprocating parts, whereby the weight is caused to move in the opposite direction to the said reciprocating parts, and with substantially the same relative velocity in the different parts of the movements, substantially as described.

2. The combination of the piston-rod of a reciprocating engine with a counter-weight and connecting-levers between the said rod and weight, constituting a parallel-motion device, whereby the said rod and weight are guided in straight paths in opposite directions, and with the same relative velocity in the different parts of their movements, substantially as described.

3. The combination of the piston-rod of an engine with levers connected at one end with the said rod, and having their other ends movable in guides at right angles to the said rod, supporting-levers connected with the said levers at an intermediate point, and themselves pivoted at an intermediate point to the framework, and a third set of levers connected at an intermediate point with the supporting-levers, and having one end movable in guides and the other end provided with weights, substantially as described.

In testimony whereof we have signed our names to this specification in the presence of two subscribing witnesses.

EDWARD BUSS.
R. KÜHN.
